UNITED STATES PATENT OFFICE

115,939

DESIGN FOR A CLOCK OR SIMILAR ARTICLE

Ivan V. Peterson, Reedley, Calif.

Application March 16, 1939, Serial No. 83,610

Term of patent 14 years

To all whom it may concern:

Be it known that I, Ivan V. Peterson, a citizen of the United States, residing at Reedley, in the county of Fresno and State of California, have invented a new, original, and ornamental Design for a Clock or Similar Article, of which the following is a specification, reference being had to the accompanying drawing, forming part thereof.

The figure is a perspective view of a clock showing my new design, both sides of which present substantially the same appearance.

My design is characterized by an artistic representation of an animal figure having forked flippers, the figure reclining on an elliptical base and supporting a clock element on its nose, all of which features as illustrated.

I claim:

The ornamental design for a clock or similar article, as shown and described.

IVAN V. PETERSON.
